CLAIM

The ornamental design for a planting table as shown and described.

DESCRIPTION

FIG. 1 is a front and right perspective view of a planting table showing our new design;

FIG. 2 is a bottom and left perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of an encircled portion 9 of FIG. 1;

FIG. 10 is an enlarged view of an encircled portion 10 of FIG. 1;

FIG. 11 is an enlarged view of an encircled portion 11 of FIG. 1;

FIG. 12 is an enlarged view of an encircled portion 12 of FIG. 1;

FIG. 13 is an enlarged view of an encircled portion 13 of FIG. 1;

FIG. 14 is an enlarged view of an encircled portion 14 of FIG. 1;

FIG. 15 is an enlarged view of an encircled portion 15 of FIG. 2; and,

FIG. 16 is an enlarged view of an encircled portion 16 of FIG. 2.

The broken lines shown in the drawings depict portions of the planting table that form no part of the claimed design. A symbolic break, shown in broken line, appears in the length of the planting table.

The break line, as well as the appearance of any portion of the planting table beyond the break line, forms no part of the claimed design. The broken lines of alternating length in

(Continued)

FIGS. 9-16 are for the purpose of illustrating the boundaries of the enlarged fragments shown in FIGS. 1-2 and form no part of the claimed design.
